UNITED STATES PATENT OFFICE.

HOWARD E. EVERETT, OF GRAND RAPIDS, MICHIGAN.

SHOE-POLISH BOX.

1,342,537.

Specification of Letters Patent. Patented June 8, 1920.

Application filed August 21, 1919. Serial No. 319,040.

To all whom it may concern:

Be it known that I, HOWARD E. EVERETT, a citizen of the United States, residing at Grand Rapids, in the county of Kent and State of Michigan, have invented certain new and useful Improvements in Shoe-Polish Boxes, of which the following is a specification.

My invention relates to improvements in shoe polish boxes and its objects are: first, to provide a shoe blacking box with which blacking may be readily pressed longitudinally of the box, and made to exude as desired for distribution upon the surface of the object being blackened, as a shoe; second, to provide a means whereby the daubing and spreading of the blacking may be rendered uniform over the surface being covered; third, to provide a means whereby the box, used as a polisher handle, may be made to assume the most desirable angle with the surface being treated; fourth to provide a means whereby the blacking box may be packed into a suit case without danger of injuring other articles in the case, and, fifth, to provide a means whereby the box may be readily refilled and reused, thus avoiding the necessary expense of purchasing a new box for blacking, as each box is exhausted, or with which the cover and distributor may, if desired, be retained to be used upon several boxes, thus rendering it possible to refill an emptied box, if desired, or to connect a new box with the old cap, which is a combined dauber, distributor and polisher.

I attain these objects by the mechanism illustrated in the accompanying drawing, in which Figure 1 is a longitudinal section of the box practically upon the line 1—1 of Fig. 2. Fig. 2 is a plan of the box complete. Fig. 3 is an elevation of the cap and polisher disconnected from the box. Fig. 4 is a transverse section of the box practically upon the line 4—4 of Fig. 2.

Fig. 5 shows the position of the box when daubing or spreading the blacking upon a surface to be blacked and polished, and Fig. 6 shows the box in the most desirable position for smoothing and polishing a surface.

Similar reference characters indicate similar parts throughout the several views.

In the drawing 1 represents the box which is a plain box or tube having a screw thread formed at one end, as at 3, and a securing

element formed at the other end, consisting of a groove formed in the end of the case for the reception of the edges of the disk 8, as at 9, the box being open at both ends. 2 represents a cap that is fitted to be screwed upon the end of the box at 3, and which has a partition 6 formed in it upon a convenient angle to allow of the box being used conveniently for polishing the surface being worked upon, as indicated in Fig. 6. This cap is, also, provided with an opening at *a* for the gradual passage of blacking from the box upon the surface being treated, and with a polishing element, as 5, which may be made of felt, as indicated, of bristles, hair, or other suitable material.

I provide for forcing the blacking through the box, and to exude out of the opening *a*, by means of a piston or like element, 11, which is mounted upon the rod 10, the two being screw threaded so that the turning of the rod in one direction, say to the right, will force the blacking against the partition 6 and out through the opening *a*, and turning the rod in the other direction will cause the element 11 to recede from the surface of the blacking back into the position indicated by its dotted lines at *b*, the latter position being necessary when the box is well filled with blacking. This rod is firmly secured upon a properly constructed head, as 7, in such a manner that the turning of the head in either direction, as to the right, or to the left, will cause the piston 11 to move longitudinally of the rod 10, as hereinbefore set forth. Inside of this head, and pivotally connected with the rod 10, as at *f*, is a disk 8 that is designed to be made to engage with the securing element 9 on the box to prevent the head 7 from being forced outwardly, away from the box when attempting to force the blacking out of the opening *a*, as hereinbefore described.

I prevent the piston 11, or the securing element 8 revolving in the box when the rod 10 is made to revolve, by forming a rib *c* in the inside of the box, running the entire length thereof, and a corresponding notch, as *d*, in both the piston 11 and the securing element 8, to slide along upon said rib. It will be understood that it is not absolutely necessary to form the notch *d* in the element 8, though I prefer it there.

To prevent the blacking exuding through the opening *a* when not desired, I have pro-

vided a cover 4 for the box that may be made to fit so closely over the end of the box as to insure perfect cleanliness when the box is laid away in a suit case, or other place 5 where, otherwise, danger would exist.

In Figs. 5 and 6 I have shown the relative positions of the box, first, when daubing or distributing the blacking upon the surface of the object, *e*, being treated, and in the 10 latter instance, in properly spreading and polishing upon the surface of the article being treated.

I wish to call particular attention to the 15 fact that the daubing element, to wit: the opening *a*, and the spreading and polishing element, to wit: the felt, or other suitable element 5, act independently of each other. Thus, I avoid permeating the entire body of the polishing element with the blacking 20 when daubing or roughly placing the blacking upon the surface to be treated. I also desire to say that while I have used the term: "shoe blacking and polishing" 25 throughout my specification, the cap is for use for all kinds of shoe dressings and polishing service, and for other uses for which it may be available, and I find that the peculiar position and form of the end or partition 6, of the cap 2 renders the passage of 30 the polish much smoother than any other form could produce. It also has the advantage of keeping the polish always moist and free flowing, as but little of the polish is exposed to the weather at one time.

35 I do not mean to restrict myself to the use of the particular elements shown for forcing the contents of the box out of it, as there are many means for producing the desired result without departing from the 40 spirit of my invention.

When preparing to refill a box after its

contents has been exhausted, I remove the cap 7, the disk 8, the rod 10 and the piston 11, or their equivalents by disengaging the disk 8 from the groove 9, and drawing the 45 cap 7, the disk 8, the rod 10 and the disk 11 off of, and out of the tube 1, and fill the box in any available or convenient manner. Or, if desired, the cap 2 may be removed and the box filled from this end without removing 50 the compressing elements hereinbefore mentioned. In the latter line of filling it will, of course, be necessary to move the piston 11 into the position indicated by its outline at *b* in Fig. 1 by revolving the screw threaded 55 rod 10, as hereinbefore stated.

What I claim as new in the art, is:

1. In a device of the kind described, an open ended cylinder having one end screw threaded, a cap fitted to be screwed onto said 60 end and having an angularly inclined partition in the cap, a spreading and polishing element secured to the partition outside of the cap, said cap having an opening immediately at the inner surface of the partition 65 through the longest side of the cap, means for forcing the blacking into the cap and out through the opening in the cap.

2. In combination with a tubular box, and an element within said box adapted to 70 force the contents of the box longitudinally toward one end of the box, a cap fitted to be securely mounted upon the discharge end of the box and having an opening through one side for the gradual discharge of the 75 contents of the box, a head wall or partition in the cap with its apex immediately at the side of said opening.

Signed at Grand Rapids, Michigan, Au-
gust 18, 1919.

HOWARD E. EVERETT.
